Inventor.

Luther R. Wallace

United States Patent Office.

LUTHER R. WALLACE, OF ADRIAN, MICHIGAN.

Letters Patent No. 90,615, dated May 25, 1869.

IMPROVEMENT IN STEAM-BOILER FURNACES.

The Schedule referred to in these Letters Patent and making part of the same.

To all whom it may concern:

Be it known that I, LUTHER R. WALLACE, of Adrian, in the county of Lenawee, and State of Michigan, have invented a new and useful Improvement in Furnaces for Steam-Boilers; and I do hereby declare that the following is a full, clear, and exact description of the construction and operation of the same, which will enable others skilled in the art to make and use my invention, reference being had to the accompanying drawings, and to the letters of reference marked thereon, similar letters referring to like parts.

The nature of my invention consists chiefly in so constructing the fire-furnaces of steam-boilers that the draught is downward through the fire instead of upward, thereby causing a more perfect combustion of the smoke and fuel, and hence realizing far more heat from a given amount of fuel.

To enable others skilled in the art to make and use my invention, I will now proceed to describe its construction and use.

In the drawings—

Figure 1 represents a longitudinal section, passing vertically through the centre of a steam-boiler, and also through the centre of my improved furnace attached.

Figure 2 represents a transverse section, passing vertically through the line X-Y in the previous figure.

Figure 3 represents a view of the cover F of the fire-furnace B.

H represents the boiler.

ff, &c., the flues.

Between the fire-furnace B and the flues, I drop down, from the upper part of the boiler H, a partition water-space, A, and produce it below the furnace-grates g, leaving a space between it and the bottom k of the air-space 1.

This partition water-space A extends the whole width of the fire-furnace, and is hollow, being formed of the same material as the boiler, and opening into it so as to be filled with water.

E is a fire-box, and intervenes between the furnace B and the flues of the boiler, and is partially separated from the furnace B by the water-space A, as shown in fig. 1 of the drawings.

i is an outside water-space, and surrounds the fire-furnace and fire-box on their four perpendicular sides, and opens into the water-space in the boiler, as shown in figs. 1 and 2 of the drawings.

n and m, figs. 1 and 2, represent two of the sides of a rectangular frame of iron, which forms the bottom of the outside water-space i, thus allowing the ashes from the furnace to fall upon the bottom k of the air-space 1.

The grates g are placed at the bottom of the furnace, after the usual manner, to hold up the fuel.

D is an ash and fire-pit, to receive the ashes and allow the heat and flame to pass from the furnace B, through the grates g, and down under the water-space A into the fire-box E, and thence upward into the boiler-flues ff, &c., thereby causing a perfect com-

bustion of the fuel, and of the smoke, in passing through the fire, and not allowing anything but heat and flame to enter the fire-box E and flues of the boiler.

The covering F of the fire-furnace B is represented in the third figure of the drawings, and it shows the two doors a and a', for supplying the furnace with fuel, and also the draught-damper S, with openings c c', and representing, by dotted lines, the water-space i and the air-space 1.

The doors are elevated obliquely to an angle of about forty-five degrees from the cover F, so that the fuel may be thrown into the fire-furnace in the direction indicated by the arrows, so as to fall upon any part of the grates g.

This is done by throwing the fuel either against the backs b and b' of the door-boxes, and letting it glance off upon the grates g, near the back side of the furnace B, or by throwing the fuel diagonally, as represented by the arrow i, to the front side of the furnace.

The fire is kindled upon the grates, in my improved furnace, in the same manner as in other furnaces, and as the coal, or other fuel, is thrown down upon it, it immediately ignites, and the smoke passes downward through the fire, where all the unconsumed particles are ignited, and a perfect combustion takes place.

In using coal for fuel, the economy is most marked in my furnace, for the draught being downward, the smoke of the coal is drawn through the fire, and consumed by a perfect combustion; whereas, by the common upward draught, the smoke passes off without being consumed, and is lost, and thus is wasted a large percentage of the real value of the coal.

Moreover, the fire in the furnace, being located between the flues of the boiler and these doors, prevents the direct action of the cold air upon the flues when the doors are opened to feed the fire.

The ash-pit will be provided with the customary opening for the withdrawal of the ashes, to be arranged on either of its sides, as preferred, and provided with a tight door, or other means for closing it.

Claims.

Having thus described my invention,

What I claim as new, and desire to secure by Letters Patent, is—

1. The arrangement of the register S, furnace or fire-chamber B, combustion-chambers D E, and flues f, substantially as represented and described, for the purpose set forth.

2. The water-space A, between the fire-furnace B and fire-box E, substantially as set forth and described.

3. The oblique backs b and b', in combination with the doors a and a', for the purposes set forth and described.

LUTHER R. WALLACE.
